UNITED STATES PATENT OFFICE.

CHESTER W. BURNHAM, OF ONEIDA, NEW YORK.

CALENDAR.

Application filed January 6, 1923. Serial No. 610,967.

To all whom it may concern:

Be it known that I, CHESTER W. BURNHAM, a citizen of the United States, and resident of Oneida, county of Madison, State of New York, have made a certain new and useful Invention Relating to Calendars, of which the following is a specification, taken in connection with the accompanying drawing, which forms part of the same.

10 This invention relates especially to merchandising calendars in which the calendar front or face which may have any suitable artistic or advertising matter and also specific or general advertising statements, is provided with one or more merchandising dates or statements which are preferably interchangeable and arranged in connection with an exhibiting opening or device by which interchangeable time period or other general merchandising statements may be exhibited, preferably in distinctive color or type so as to correspond with the adjacent merchandising date or statement with which they are to cooperate. For this purpose a suitable opening may be arranged in the calendar front and a movable change disc, horizontal endless tape or other movable exhibiting member may be arranged on the back of the calendar so as to support the calendar if desired and also to make visible through this opening the desired number of days, weeks or other time period or general merchandising statements in connection with the merchandising date or statement on the front of the calendar which may be advantageously placed below this exhibiting opening.

15 In the accompanying drawing showing in a somewhat diagrammatic way an illustrative embodiment of this invention:

20 Fig. 1 is a front view

25 Fig. 2 shows interchangeable merchandising or time statements which may be used on the calendar

30 Fig. 3 is a rear view of the calendar, and

35 Fig. 4 is a front view of the detached change disc therefor.

The calendar may be made of any suitable material and construction and for many purposes it is desirable to form the calendar of heavy cardboard on which the advertising or other material may be printed or otherwise reproduced. As shown in Fig. 1, the calendar front 1 may have hinged or connected thereto the folding supporting wings 2 which may be joined to the calendar front

as by the cloth or other flexible hinge strips 18 shown in Fig. 3. In this way the supporting wings may during shipping be folded inward over the lower part of the calendar front, while in use these wings may be 60 swung outward into some such supporting position as is indicated in Fig. 1 so as to support the calendar front on a table or counter and contribute to the general design features thereof. This calendar front may have any 65 desired artistic design printed or pasted thereon so as to make the calendar attractive in connection with its general colored or other design features, and specific and general advertising statements of any desired character may be applied to the calendar front and wings so as to make a desirable advertising exhibit for the general trade for which the calendar is designed, such as 70 the jewelry or silverware trade in the case 75 of this calendar, which is particularly designed for use in connection with silver table ware.

At the upper or lower part of the calendar front in connection, if desired, with such advertising statements, an exhibiting opening such as 3 may be formed preferably above or adjacent a merchandising date or statement such as 4, which is preferably in some distinctive color or type of lettering. A 80 change disc or movable exhibiting device such as 9 may be arranged in connection with this exhibiting opening so as to make visible therethrough one or more of the time period or other merchandising statements such as 5 90 which are on this disc or member and which are preferably printed in correspondingly distinctive color or type to the merchandising statement 4. This change disc 9 may, as indicated in Figs. 3 and 4, be detachably 95 pivoted to the calendar front or body as by the disengageable pivot connection 17, the two ends of which may be forced together and then this change disc 9 may be withdrawn from the pivot and reversed before 100 again pushing the pivot through the opening 8 in the center 7 of this disc so as to exhibit the indications on its opposite side. Where such a double face change disc is used it is desirable to have an inner locating set of 105 designations 11 which correspond to the outer exhibiting time period or other merchandising statements 5 on the opposite side of the disc, see Figs. 3 and 4. In the same way the inner set of designations 10 corre- 110

spond to the outer exhibiting designations 12 on the other side of the disc so that any of these time period or other statements may be brought into alignment with the exhibiting opening by bringing the inner locating designations such as 10, or 11 into engagement with a suitable indicator on the back of the calendar. This indicator may comprise the arrows 14 on the body 15 more or less extending or bridging over the outer part of this change disc while an indicator support 13 is glued or otherwise attached to the calendar back so as to support this indicator properly and yet allow the disc to be removed or replaced, as desired. This arrangement makes possible the consideration of the various time period or other merchandising statements by inspecting the back of this change disc where practically all of the indications or statements which can be used by reversing the disc are visible directly while the inner locating designations are all visible which correspond to the regular time period or other statements which can be shown through the indicating opening by merely turning this change disc and without reversing the same by removing it from its pivot. In the position of the parts shown in Figs. 1 and 3 the indicator is aligned with the inner locating designation 16 as shown in Fig. 3, which automatically brings the corresponding exhibiting designation or time statement 5 in front of the exhibiting opening 3 in the calendar front shown in Fig. 1. For some purposes it is desirable to have still other interchangeable or detachable time period or other merchandising statements such as the pasters or labels 6 shown in Fig. 2 which may be pasted on this change disc to replace other indications thereon when desired.

In the use of this calendar the appropriate merchandising date or statement is used in connection with the exhibiting opening or portion and several interchangeable dates or statements such as 4 shown in Fig. 2 are provided so as to be attached to the calendar front and cover the gift or shopping periods, such as Christmas, Thanksgiving, Easter, etc.; also more general merchandising statements such as "For wedding gifts", may also be made up in label or paster form so as to be applied to the calendar front in the desired distinctive color or type to cooperate with the exhibiting opening or portion. The change disc may, as described, exhibit the desired number of days, weeks, or other time period in connection with the appropriate merchandising date on the calendar front and in this way the purchasing public can be reminded of the remaining period before Christmas, for example. If desired, however, the more general merchandising statements on the change disc or member may be brought into connection with the opening such as "Shop early", "See our full stock", "Select silver gifts", "Buy here", "Buy silverware", which may be used either in connection with the merchandising dates such as mentioned, or in connection with the more general merchandising statements such as "For wedding gifts", or "For birthday gifts", which may be exhibited on the face of the calendar in this connection. In this way the dealer or tradesman has a merchandising calendar which can be used for a long period of time or indefinitely and has sufficient interchangeable features so that it can be altered appropriately to correspond with various dates or periods throughout the year and have general advertising or selling value in connection with the type of merchandise for which the general advertising and other merchandising statements are adapted. This is naturally of distinct advantage from the advertiser's standpoint, since his specific merchandise is continually brought to the attention of the public as long as the calendar retains its usefulness from the dealer's standpoint.

This invention has been described in connection with various illustrative forms, proportions, and devices, indications, advertising and merchandising statements, to the details of which disclosure the invention is not of course to be limited since what is claimed as new and what is desired to be secured by Letters Patent is set forth in the appended claims.

I claim:

1. The merchandising calendar comprising a calendar front formed with folding supporting wings adapted to be arranged in substantially flat close contact with the calendar front for shipping purposes, the calendar front being provided with decorative and advertising matter comprising specific and general advertising statements and with an exhibiting opening adjacent the lower part of the calendar in connection with an interchangeable merchandising date statement of distinctive appearance, and a double face change disc detachably pivoted to the calendar back and formed with an outer series of exhibiting time period and general merchandising statements of the same distinctive appearance on both sides of the disc to be shown through said exhibiting opening in the calendar front and inner series of locating designations adapted to cooperate with an indicator on the rear of the calendar to thereby indicate the exhibiting statement on the opposite side of the change disc which is visible through said indicating opening.
2. A calendar comprising a front section having an exhibiting opening, a reversible disc rotatably and detachably connected with the front section and provided on each face with a series of exhibiting statements.

in alignment with and adapted, by rotation of the disc, to be separately exhibited through said exhibiting opening and with a second series of indicating statements out of alignment with said opening, the statements of said second series on each side of the disc referring to the exhibiting statements on the other, and means coacting with said indicating statements for indicating the exhibiting statements as presented at the exhibiting opening.

3. A calendar comprising a front section having foldable supporting means and an exhibiting opening, a reversible disc rotatably and detachably connected with the front section and provided on each face with a series of exhibiting statements in alignment with and adapted, by rotation of the disc, to be separately exhibited through said exhibiting opening and with a second series of indicating statements out of alignment with said opening, the statements of said second series on each side of the disc referring to the exhibiting statements on the other, and means coacting with said indicating statements for indicating the exhibiting statements as presented at the exhibiting opening.

4. A calendar comprising a front section having foldable supporting side wings and an exhibiting opening, a reversible disc rotatably and detachably connected with the front section and provided on each face with a series of exhibiting statements in alignment with and adapted, by rotation of the disc, to be separately exhibited through said exhibiting opening and with a second series of indicating statements out of alignment with said opening, the statements of said second series on each side of the disc referring to the exhibiting statements on the other, and means coacting with said indicating statements for indicating the exhibiting statement as presented at the exhibiting opening.

45 5. A calendar comprising a front section having decorative and advertising matter on its front face, an exhibiting opening and a space associated therewith for interchangeable merchandising date statements, a reversible disc rotatably and detachably connected with the front section and provided on each face with a series of exhibiting

statements in alignment with and adapted, by rotation of the disc, to be separately exhibited through said exhibiting opening and with a second series of indicating statements out of alignment with said opening, the statements of said second series on each side of the disc referring to the exhibiting statements on the other, and means coacting with said indicating statements for indicating the exhibiting statements as presented at the exhibiting opening.

6. A calendar comprising a front section having decorative and advertising matter on its front face, foldable supporting means, an exhibiting opening and a space associated therewith for interchangeable merchandising date statements, a reversible disc rotatably and detachably connected with the front section and provided on each face with a series of exhibiting statements in alignment with and adapted, by rotation of the disc, to be separately exhibited through said exhibiting opening and with a second series of indicating statements out of alignment with said opening, the statements of said second series on each side of the disc referring to the exhibiting statements on the other, and means coacting with said indicating statements for indicating the exhibiting statements as presented at the exhibiting opening.

7. A calendar comprising a front section having decorative and advertising matter on its front face, foldable supporting side wings, an exhibiting opening and a space associated therewith for interchangeable merchandising date statements, a reversible disc rotatably and detachably connected with the front section and provided on each face with a series of exhibiting statements in alignment with and adapted, by rotation of the disc, to be separately exhibited through said exhibiting opening and with a second series of indicating statements out of alignment with said opening, the statements of said second series on each side of the disc referring to the exhibiting statements on the other, and means coacting with said indicating statements for indicating the exhibiting statements as presented at the exhibiting opening.

CHESTER W. BURNHAM.
